DISTRIBUTOR

Marion Mallory, Detroit, Mich., assignor to
 Mallory Research Company, Toledo, Ohio, a
 corporation of Ohio

Application May 18, 1933, Serial No. 671,667

3 Claims. (Cl. 200—19)

The object of this invention is to reduce the cost of the distributor cover and to improve its reliability under severe service conditions.

An additional object is to reduce the electrical interference with radio reception.

The distributors now in use on automobiles for distributing the high tension electricity to the spark plugs are either expensive to make, or, if they are made cheaper, are not reliable, especially when subjected to moist air and rain.

The problem to be solved was to make an inexpensive distributor that could not be shorted by wet air being blown over it.

In the drawings:—

Figure 1 shows the preferred form of my invention as used on an automobile ignition device, being a cross-sectional elevation taken on plane 1—1 of Figure 2.

Figure 2 is a plan view of Figure 1 looking down.

Figure 3 shows an improved cover construction applied to a high tension ignition coil, being a cross-sectional elevation taken on plane 3—3 of Figure 4.

Figure 4 is a plan view looking down on Figure 3.

Figure 5 shows an alternative construction, being a cross-sectional elevation taken on plane 5—5 of Figure 6.

Figure 6 is a plan view looking down on Figure 5.

Figure 7 shows the distributor more in detail, together with the specific details directed to the elimination of radio interference, being a cross-sectional elevation taken on plane 7—7 of Figure 8.

Figure 8 is a plan view looking up on Figure 7.

Figure 9 is a view of an enlarged portion of Figure 7.

Figure 10 is another enlarged view of Figure 7.

Figure 11 is another enlarged view of Figure 7.

In these figures, the chief novel feature of my invention resides in the provision of the circular rubber pad or cushion 11 enclosed in a bakelite or metallic cover 12. See Figs. 1, 3 and 5. 13 and 14 are two of the high tension terminals mounted in the roof 16 of the distributor housing 15. 17 is the high tension lead through which all the electricity flows, which

is subsequently distributed through the high tension terminals 13 and 14. The high tension lead 17 is made a tight fit in the rubber pad 11, which pad 11 is held tightly down by the clamps 18 and 19. A central terminal 20, located in the roof 16, receives the high tension current from

17 by the contact created by the pressure exerted by the clamps 18 and 19. The high tension electricity, which enters at 17, is distributed to 13 and 14 in the manner shown in Figure 7. High tension wires 21, 22, 23, 24, 25 and 26 are forced into the rubber disc 11 in the same way that 17 was forced into the disc 11. These wires are pressed down to their high tension terminals 13, 14 etc. by the clamps 18 and 19. The rubber pad 11 yields sufficiently so as to make a watertight connection with the cables and also with the roof 16. Water is thus prevented from reaching the actual metal to metal contact where the exposed ends of the cables 17, 23, 25 etc. touch the high tension terminals 20, 14, 13 etc. 15

In Figure 3, a rubber pad 31 and bakelite cover 32 (which may, of course, be a metal cover) are pressed down onto the top of the coil 47 by means of two screws 28 and 29, which take the place of the spring clamps 18 and 19 of 20 Figures 1 and 2. This coil has a high tension terminal 30, against which the exposed end of the high tension terminal 17 is pressed when the rubber pad 31 is pressed down onto the coil by means of the screws 28 and 29. 25

In Figure 7 and Figure 8 is illustrated the means for preventing the distribution of the high tension current disturbing the radio reception on a car. 33 is the high tension entrance connection. 49 is one of the contacts to which this high tension electricity is distributed. 34 is the movable high tension connection located between 33 and the group of high tension terminals of which one only, 49, is illustrated in Figure 7. The movable connection 34 is mounted on the rotating insulated arm 35, which is mounted on the end of the cam shaft 36. In Figure 8 is illustrated a circular groove or annular trough 37. Into this groove, the terminals 49 etc. project flush with the walls of the groove 37. This groove is split up into six portions by six projections, 50. 30 35 40

The outer end of the conducting strip 34 carries a contact disc 38, which is pressed onto the annular walls of the circular groove 37 by the spring tension, which is built into the strip 34. The clearance between 38 and 49 can thus be reduced to a minimum. 45

All the other details of Figure 7 are identical with the construction shown in Figure 1, which 50 has already been described, except that a screw 51 is substituted for the clamps 18 and 19.

In Figures 9, 10 and 11, enlarged detailed views of Figure 7 are shown. A conical shoulder 53 is shown projecting from the rubber pad 11 and 55

engaging with a curved fillet 52 in the top of the distributor housing 16.

The purpose of this conical projection 53 and the curved surface 52 is to ensure that there is no leakage and also to lock the wire 13 into the rubber pad 11 and thus prevent it working loose.

What I claim is:—

1. A cover for a high tension distributor comprising a relatively soft rubber pad, high tension wires imbedded in said pad, a casing of relatively hard material protecting the outside surface of said pad, means for clamping the exposed surface of said soft rubber pad against the top of said distributor for the purpose described.
- 10 2. In an ignition circuit for internal combustion engines, means for connecting a high tension wire to a high tension terminal comprising a cover having a casing of relatively hard material, a soft

rubber pad within said casing, high tension wires imbedded in said pad and projecting therefrom, means for pressing said cover to said terminal so that the high tension wire is held in contact with said terminal.

- 15 3. In an ignition circuit for internal combustion engines, means for connecting a high tension wire to a high tension terminal comprising a cover having a casing of relatively hard material, a soft rubber pad within said casing, high tension wires imbedded in said pad and projecting therefrom, a conical projection surrounding the wire as it projects from the pad, means for pressing said cover to said terminal so that the high tension wire is held in contact with said terminal and the conical projection crushed against said high tension wire.

MARION MALLORY.
